UNITED STATES PATENT OFFICE.

LACHLAN MACLACHLAN, OF GRAND RAPIDS, MICHIGAN, ASSIGNOR TO CHENEY
TALKING MACHINE COMPANY, OF CHICAGO, ILLINOIS, A CORPORATION OF ILLINOIS.

DESIGN FOR A PHONOGRAPH CABINET.

61,203.

Specification for Design.

Patented July 11, 1922.

Application filed November 7, 1921. Serial No. 513,597. Term of patent 7 years.

To all whom it may concern:

Be it known that I, LACHLAN MACLACHLAN, a citizen of the United States, residing at Grand Rapids, in the county of Kent and State of Michigan, have invented a new and original Ornamental Design for Phonograph Cabinets, of which the following is a specification, reference being had to the accompanying drawing, forming a part thereof.

The figure is a front elevational view of a phonograph cabinet showing my new design.

I claim:

The ornamental design for a phonograph cabinet, as shown.

LACHLAN MACLACHLAN.
